his Attorney.

UNITED STATES PATENT OFFICE.

WALTER L. THORNE, OF CINCINNATI, OHIO.

LASTING-TACK PULLER.

1,101,105.

Specification of Letters Patent. Patented June 23, 1914.

Application filed March 18, 1914. Serial No. 825,534.

To all whom it may concern:

Be it known that I, WALTER L. THORNE, a citizen of the United States, residing at Cincinnati, in the county of Hamilton and State of Ohio, have invented certain new and useful Improvements in Lasting-Tack Pullers, of which the following is a specification.

Lasting-tacks are employed in the manufacture of shoes to temporarily secure the upper of the shoe in stretched relation over the last. These lasting-tacks are supposed to be removed from the shoe during its course of manufacture, so that the finished shoe shall not contain the same. In practice, however, due to negligence, lasting-tacks at times remain in the shoe, so that when the shoe is tried on or worn, the presence of the lasting-tack is discovered. It has heretofore been a difficult operation to remove lasting-tacks of this character from the shoe, for the reason that the point-ends of the tacks extend into the interior of the shoe, the head-end of the tacks being between the turned-over portion of the upper and the outer sole, or between the outer sole and the insole of the shoe, and because these lasting-tacks are liable to be adjacent to the edge or at the extreme toe-end of the inner portion of the shoe, where it is extremely difficult to reach the same. It has been found in practice, that unless lasting-tacks of this character are entirely removed, that they will cause annoyance or pain to the wearer of the shoe from time to time, even if the tacks are snipped and blunted by hammering from time to time.

It is the object of my invention to provide an improved lasting-tack puller, by means of which it is possible to reach all portions in the interior of the shoe for gripping the lasting-tack and pulling the same out of the shoe bodily.

The invention will be further readily understood from the following description and claims, and from the drawing, in which latter:

Figure 1 is a perspective view of my improved lasting-tack puller, shown in operative position in a shoe, the latter being shown in perspective and partly broken away. Fig. 2 is a side elevation of my im-

proved device. Fig. 3 is a plan section taken on the line 3—3 of Fig. 2. Fig. 4 is a vertical section taken on a line corresponding to the line 4—4 of Fig. 3. Fig. 5 is a vertical cross-section taken on the line 5—5 of Fig. 3. Fig. 6 is an end view of the claw-head, the stem being shown in section on the line 6—6 of Fig. 2; and, Fig. 7 is a perspective and enlarged view of the head-end of my improved device shown in a shoe in position of use, the shoe being partly broken away.

A shoe is exemplified at 11, in which a lasting-tack 12 is shown in one of the forms and relations in which a lasting-tack of this character is left after the completion of the shoe. These lasting-tacks usually extend inwardly above the insole 13 of the shoe, and in practice are sometimes straight and at other times bent in various ways and projecting in different directions in the inside of the shoe. The head 14 of the lasting-tack is usually between the inturned edge 15 of the shoe-upper 16 and the outer sole 17 of the shoe.

My improved device is arranged so as to engage the inwardly projecting portion of the shank 18 of the lasting-tack in such manner that the lasting-tack is thereby raised from the insole, if it lies flush with or is adjacent to the insole, and may be shifted or straightened out for proper gripping thereof by the lasting-tack puller, preparatory to the pulling of the lasting-tack out of the shoe by my improved device.

My improved lasting-tack puller is shown at 21, and comprises a stem 22 which has a bend 23 therein, for forming an upwardly and outwardly extending portion 24 and a substantially horizontally and inwardly extending portion 25 of the stem, at the outer end of which latter portion an acute bend 26 is formed, from which a claw-head 27 extends substantially parallel to the substantially horizontally extending portion 25 of the stem.

Several claw-teeth 31, 31, 32, 32, are formed on the claw-head, for forming a plurality of lasting-tack slots 33, 34, 34, between them. I prefer that the outer ends of the claw-teeth 31, 31, project in advance of and between the claw-teeth 32, 32, for the purpose hereinafter explained.

The tack-slots 33, 34, 34, preferably have comparatively wide outwardly flaring mouths 35, 36, 36, and side walls in rear of said wide outwardly flaring mouths, the side walls of 5 said respective slots in rear of each of said outwardly flaring mouths being substantially parallel with each other and respectively having a lower edge 39, which is comparatively sharp, for indenting the shank of the 10 lasting-tack, the proximate lower edges of the respective slots, however, preferably not approaching each other sufficiently closely to cause a clipping or cutting of the tack, the inner end wall 40 of the slot being preferably blunt and substantially perpendicular 15 to the plane of the lower face 41 of the claw-head. The side walls of the respective slots, above said lower edges 39, are formed with a longitudinal rounding, as shown at 20 42, for forming upper inwardly projecting edges 43 at the upper ends of said walls. The outer ends of the teeth slope downwardly and outwardly toward the lower faces of said teeth as shown at 44 for being 25 readily received under the points or the shanks of the tacks that may be closely pressed against the insole of the shoe.

If it is desired to remove a tack, the claw-end of the instrument is introduced into the 30 shoe, with its claw-end at about the location of the tack, and then moved about and manipulated by the handle 45 until the tack is contacted. My improved device is then manually manipulated until the tack enters one 35 of the slots. The form of the device, as well as the arrangement of the teeth of the claw-head, permits the stem of the device to be projected in various directions with relation to the shoe, either parallel to the length of 40 the shoe or crosswise of said length, so that a lasting-tack in the middle of the sole of shoe, or at the side edge or extreme toe of the shoe may engage in one of the slots. These tacks are liable to extend in any direction, or be in any relation to the insole. For 45 instance, the outwardly and downwardly tapering outer ends of the teeth permit ready engagement of the teeth, the outer ones of which are shown shorter than the inner ones, under the tack, irrespective of its location in the shoe, and the comparatively wide mouths of the slots insure entrance of the tack into one of the slots. As soon as the tack enters one of the slots, the comparatively 50 sharp lower edges of the walls of the slot will dig slightly into the opposite sides of the tack for getting a firm grip thereon, a severing of the shank of the tack being however avoided by the spacing between the side 55 walls and the form of the slot.

It is advisable that the shank of the tack be projected upwardly prior to the pulling action of the device. This is readily accomplished by the form of the walls of the slot,

wherein the upper edge of the wall forms an 65 inwardly projecting ledge adapted to engage the shank of the tack above its lower end, in which relation, if a slight turn is given to the stem of the puller about its axis, a straightening of the tack is effected, for 70 permitting ready passage of the walls of the slot lengthwise of the tack.

When the tack has been firmly engaged by the walls of one of the slots, it may be readily pulled out of the leather and through the 75 insole, either by a turning movement of the puller about the axis of its stem, or by a leverage motion obtained by tilting the puller either upon the toe-ends 46 of the claws or upon the heel-end 47 thereof, or by 80 a direct pulling upon the puller longitudinally of its shank.

Having thus fully described my invention, what I claim as new and desire to secure by Letters Patent, is:

1. A lasting-tack puller comprising a stem-portion and a reversely extending claw-head extending substantially parallel to said stem-portion, said claw-head comprising claw-teeth having a lasting-tack shank-receiving slot between them the walls of which are formed with proximate lower sharp edges projecting toward each other and arranged for indenting the side of the shank of said lasting-tack, mutually receding grooved portions above said lower edges which extend lengthwise of said walls, and upper proximate edges which project toward each other above said last-named wall-portions lengthwise of said walls, and said last-named 100 proximate edges being spaced apart a greater distance than said first-named proximate edges.

2. A lasting-tack puller comprising a stem-portion and a reversely extending claw-head connected with said stem-portion by a curve and extending substantially parallel therewith, said claw-head comprising several claw-teeth located side by side and having a plurality of lasting-tack receiving slots 110 therebetween, the sides of said teeth forming the side walls of said slots having lower proximate edges extending toward each other, the outer ends of said teeth being tapered downwardly and outwardly for forming widening mouths for said slots, and said slots having blunt inner ends, whereby said lower proximate edges of said side walls of said slots are arranged to indent the shanks of the lasting-tacks and the rear walls 115 of said slots are arranged for preventing severance of said shanks.

3. A lasting-tack puller comprising a stem-portion and a reversely extending claw-head connected with said stem-portion by a 125 curve, said claw-head being substantially parallel to said stem-portion, said claw-head comprising several claw-teeth located side by

side having a plurality of lasting-tack receiving slots therebetween the outer ends of which have outwardly flaring mouths, and the inner ones of said teeth being longer than the respective outer ones of said teeth, substantially as and for the purpose specified.

In testimony whereof, I have hereunto signed my name in the presence of two subscribing witnesses.

WALTER L. THORNE.
